The ornamental design for a propane cylinder storage cabinet, as shown and described.

DESCRIPTION

FIG. 1 is a front view showing my new design;

FIG. 2 is a bottom view thereof;

FIG. 3 is a perspective view thereof with one of the doors shown in an opened position. The side of the storage cabinet that is not shown is identical to the side of the cabinet that is shown. The rear of the cabinet is plain and unornamented; and,

FIG. 4 is a perspective view of another embodiment thereof.
